UNITED STATES PATENT OFFICE.

OSCAR F. OLSON, OF BETHLEHEM, PENNSYLVANIA.

ROUNDABOUT.

Application filed February 11, 1922. Serial No. 535,841.

To all whom it may concern:

Be it known that I, OSCAR F. OLSON, a citizen of the United States, residing at Bethlehem, in the county of Northampton and State of Pennsylvania, have invented new and useful Improvements in Roundabouts, of which the following is a specification.

This invention relates to amusement devices and particularly to devices for giving patrons a ride of a novel character.

The principal object is to provide a device of this nature in which a variety of different circular motions may be imparted to the passenger carrying car.

Another object is to produce a novel and efficient means for effecting these various motions automatically.

Another object is to produce a device of this nature which shall be simple of construction, comparatively inexpensive to manufacture, and highly efficient for the purpose for which it is intended.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is an elevation view of the improved amusement device.

Figure 2 is a vertical sectional view of the same.

Figure 3 is a vertical sectional view taken at right angle to Figure 2.

Figure 4 is a bottom view of the carriage.

Figure 5 is a top view of the carriage.

Figure 6 is a sectional view through the car and carriage.

Like characters of reference refer to like parts in all views.

Referring in detail to the drawing, 10 represents a motor which may be of any suitable type for the purpose and which effects operation of a shaft 11 carrying a master gear 12 to which may be carried a plurality of wheels 13. Each of the wheels 13 is connected to identically similar devices, and only one of these connected devices is shown in the drawing, and as all are precisely alike only one is here described, although it is to be understood that it is intended to drive several of these devices from a single motor source.

A circular track is provided comprising an inner rail 14 and an outer rail 15 and upon these rails are mounted respective wheels 16 and 17 carrying a cage structure 60 which will presently be described. The inner wheel 16 is connected by a shaft 18 with the respective gear 13.

The cage structure comprises a pair of hubs 19 secured to the respective wheels 16 65 and 17, and supporting a plurality of bars 20 which are curved so that said bars and hubs together form a globular cage, which rides upon the tracks 14 and 15 and is rotated by means of the shaft 18. 70

Inside this cage there are provided a pair of circular rails 21 which are arranged parallel to each other, but at an angle to the axis of rotation of said globe which angle is other than a right angle, the preferred 75 form being an angle of from 10° to 30° from the transverse plan of the axis of rotation of the cage. It will be seen that if a carriage is mounted on the tracks 21 and gravity keeps the same at the bottom of the 80 cage, then upon rotation of the cage, the car will move in the direction of the axis of rotation back and forth a distance commensurate to the distance which the tracks are deflected from the transverse plan. 85

Such a carriage is provided and comprises a base plate 22 inside plates 23, the latter carrying bearings for a plurality of wheels 24 which ride on the upper surface of the tracks 21 and a plurality of guide 90 wheels 25 which bear against the inner surfaces of tracks 21 so as to prevent the carriage from slipping from the rails. At the center of the base plate 22 there is provided a stub shaft 26 which extends downwardly from the base plate and also upwardly therefrom. The downward extension of shaft 26 is mounted for rotation in a bearing formed in a block 27 mounted slidably on a bail 28 which is pivotally 100 mounted concentric with the axis of rotation of the globular cage.

A passenger car 29 is provided centrally of its bottom with a bearing into which the upwardly extending portion of shaft 26 105 extends. The car is also provided on its bottom with a ratchet wheel 30 whereby the car 29 may be rotated on the shaft 26 by means which will now be described.

Slidably engaging the bail 28 are channel shaped grips 31 and 32 which are connected upon respective slides 33 and 34

slidably mounted on the base 22 of the carriage. The block 33 carries on its upper surface a spring pressed ratchet pawl 35. Connected to the block or slide 34 is an 5 arm 36 which carries an arcuate rack 37 meshing with a pinion 38 carried by a bracket 39. Pinion 38 also meshes with a rack 40 depending from a slide block 41 mounted in the base plate 22. The slide block 41 carries on its upper surface a spring pressed ratchet pawl 42, the pawls 35 and 42 both engaging the ratchet wheel 30.

From the construction above described, 15 it will be seen that as the cage is rotated by means of the motor as will be readily understood, the carriage will ride along the tracks 21 and owing to the angular arrangement of said tracks will take a zig-zag 20 course moving outwardly during one-half of the rotation and inwardly during the other half of the rotation. This turns the carriage on the axis of shaft 26 and as the channel shaped grips 31 and 32 are held 25 constantly in engagement with the bail 28, the carriage will move relatively to the slides 33 and 34 thereby bringing the ratchet pawls 35 and 42 into operation on the ratchet wheel 30, the pawl 35 taking effect 30 as the carriage is moved inwardly, and the pawl 42 taking effect as the carriage moves outwardly. In this manner there is obtained 35 the following motions: (1) rotation about the motor shaft on the tracks 14 and 15, (2) movement of the carriage from side to side in the basket (3) rotary movement of the car about the axis 26. Besides, the cage revolving about the carriage and the car gives the effect to the passenger of another movement. 40

In order to obtain easy access to the car one of the bars 20 is provided with a central joint 43 which telescopes at one end over a reduced portion of the bar, and is 45 provided at the other end with a slide lock 44 whereby this section of the bar may be locked in place.

While I have described what I deem to be the most desirable embodiments of my invention, it is obvious that many of the 50 details may be varied without in any way departing from the spirit of my invention, and I therefore do not limit myself to the exact details of construction herein set forth 55 nor to anything less than the whole of my invention limited only by the appended claims.

What is claimed as new is:—

1. An amusement device comprising a circular track, a globular cage mounted for rotation over said track, means for rotating said globular cage, an endless track mounted 60 interiorly of said cage at an angle to the axis of rotation of said cage, the angle being less than ninety degrees, a car mounted

for backward and forward movement over said track and in the path of said circular track upon rotation of said globular cage.

2. An amusement device comprising a circular track, a globular cage, means for 70 mounting said globular cage upon said track for travel thereon, means for revolving said cage along said track, an endless track encircling the interior of said globular cage at an angle to the axis of rotation of said 75 globular cage, the angle of the track being less than ninety degrees, a carriage mounted within said globular cage and on said last track, a bail swingingly mounted in said 80 globular cage, a car mounted for rotation on said carriage, and means on said carriage for co-action with said bail to rotate said car.

3. An amusement device comprising a circular track, a globular cage, means for 85 mounting said globular cage upon said track for travel thereon, means for revolving said cage along said track, an endless track mounted interiorly of said globular cage at an angle to the axis of rotation of said 90 globular cage, the angle being less than a right angle, a carriage mounted on said endless track, and movable laterally within said cage upon revolving of the same by reason 95 of the angle of said track, a car rotatably mounted on said carriage, and a ratchet means carried by said carriage and operable by a swinging member upon rotation of said globular cage to impart rotation to said car. 100

4. A device of the class described comprising a globular member, means for rotating said globular member, a track secured interiorly of said globular member at an angle to the axis of rotation of said globular member the angle being less than a right angle, 105 and a carriage mounted on said track and operable thereby for movement in the direction of the axis of rotation of said globular member.

5. A device of the class described comprising a carriage, a stub shaft mounted on said carriage, a car mounted for rotation on said stub shaft, a bail, and means on said carriage adapted to co-act with said bail for rotating said car. 110

6. In a device of the class described the combination of a globular member, means for rotating said globular member, a track secured interiorly of said globular member, a bail mounted freely concentric with the axis of rotation of said globular member, a carriage mounted for movement on said track, a car rotatable on said carriage, and ratchet means on said carriage and operable by said bail for effecting rotation of said car. 115

7. In a device of the class described comprising a motor, gearing driven thereby, a plurality of shafts driven by said gear, a circular track, a plurality of globular mem- 120

- bers each operable by means of said shafts, to travel along said track, an endless track secured interiorly of said globular member at an angle to the axis of rotation of said globular member the angle being less than ninety degrees, passenger receiving means interiorly of said globular members and mounted for movement on said endless track upon the rotation of said globular member.
- 10 8. In a device of the class described the combination of a motor, a shaft driven by said motor, a globular member rotatable by said shaft, a track upon which said globular member is mounted for travel, a track supported interiorly of said globular member, a carriage mounted for movement relatively to said track and for movement by said track relatively to said globular member, and a car mounted for rotation on said carriage and operable by movement of said carriage as and for the purpose set forth.
9. A device of the class described comprising a circular track, a globular member mounted for rotation over said track, means for rotating said globular member, an endless track encircling the interior of said globular member, a carriage mounted for movement over said last mentioned track, a car rotatably mounted on said carriage, a bail swingingly mounted within said globular member, and a ratchet means on said carriage for co-action with said bail for rotating said car upon rotation of said globular member.
- 15 10. In testimony whereof I have affixed my signature.

OSCAR F. OLSON.
